UNITED STATES PATENT OFFICE.

ABBOT AUGUSTUS LOW, OF NEW YORK, N. Y., ASSIGNOR TO THE ALDEN
TYPE MACHINE COMPANY, OF SAME PLACE.

TYPE-DISTRIBUTING APPARATUS.

SPECIFICATION forming part of Letters Patent No. 618,475, dated January 31, 1899.

Application filed December 31, 1897. Serial No. 664,822. (No model.)

To all whom it may concern:

Be it known that I, ABBOT AUGUSTUS LOW, a citizen of the United States, residing in the city of New York, (Brooklyn,) in the county 5 of Kings and State of New York, have invented certain new and useful Improvements in Type-Distributing Apparatus, of which the following is a specification sufficient to enable others skilled in the art to which the invention 10 appertains to make and use the same.

My invention relates to the form of type-distributing machines disclosed in Patent No. 245,562, dated August 9, 1881, in which the types are taken one by one from the end of a line, transferred to a conveyer, and deposited 15 from the latter onto a type-distributing mechanism below; and the invention consists, essentially, in limiting and restricting the downward thrust of the pusher by which the type 20 is ejected from the conveyer substantially in the manner as hereinafter set forth.

In the accompanying drawings, Figure 1 is a sectional elevation through the conveyer and adjoining parts in the position in which 25 the types are received by the conveyer. Fig. 2 is a similar view of the conveyer, &c., at the moment of delivering the type; and Fig. 3 an edge view of the conveyer and adjoining parts.

A is the lifter by which the first type in a 30 channel *a* is detached and raised into position to be grasped by the oscillating nippers *B*, by which the type is delivered to the conveyer *C*, which serves to deposit the same on a distributer standing ready to receive it. The 35 nippers are composed of two jaws *b* *b'*, which are mounted on a pin *b*², having its bearing in the standard *S*, which rises from the carriage supporting the type-channel. The pin *b*² turns freely in the standard *S*, and the jaw 40 *b* is firmly secured to the pin, while the jaw *b'* turns loosely thereon, being drawn up toward the jaw *b* by a spring, as will be readily understood by reference to the patent hereinbefore referred to.

45 The jaw *b'* is longer than the jaw *b*, so that when the nippers swing back over the type the jaw *b* passes over its head, while the jaw *b'* is arrested by reason of the pin *b*³ on the said jaw encountering the projection *b*⁴, ex- 50 tending from the standard *S*. Thus the mo-

tion of the loose jaw is arrested just before it strikes the first type in a channel *a*, while the rigid jaw *b* proceeds and thereby the nippers are opened. At this moment the action of the lifter *A* takes place and the jaw *b* of the nippers is carried back toward the jaw *b'*, the nippers closing up and grasping the type and carrying it out to the position shown in Fig. 1. By this outward motion of the nippers the type is carried between the jaws of the conveyer *C*, as the nippers are somewhat narrower than the type, the jaws of the conveyer close up as the type is grasped by said jaws and taken from the nippers, and then deposited on the distributer as heretofore. 65

The jaws of the conveyer are mounted on a rock-shaft *R*, which has its bearings in a bifurcated standard *R'*, rising from the base-cylinder. Said conveyer consists of two jaws *C* *C'*, which are connected by a hinged joint *c*³. The jaw *C'* is pivotally mounted on the rock-shaft *R*, while the jaw *C*² turns loosely thereon and is adapted to open from or close up to the rigid jaw. In this rigid jaw is secured a spring-bolt *c*⁴, which tends constantly 70 to open the loose jaw. The inward thrust of the said loose jaw is effected by mechanism described in said patent hereinbefore referred to and need not here be described.

On the inner surface of the rigid jaw *C'* is 80 secured the pusher *P*, which consists of a **U**-shaped lever having its fulcrum on a pivot *p*. Its tail is connected to a lever *p'*, which extends from the upper edge of the rigid jaw *C'*. On the upper end of the lever *p'* is secured the roller-stud, which engages with a cam *D*, secured to the standard *R'*. When the conveyer is moved from the position shown in Fig. 1 to that shown in Fig. 2, the pusher *P* is forced outward by the action of 85 the cam on the lever *p'*, and the type previously held between the jaws is deposited 90 upon the distributer underneath.

Thus far the description has been that of the construction and operation of the machine as heretofore known and used. 95

The distinguishing feature of my present construction consists in limiting the downward thrust of the pusher *P*, so that while the pusher loosens and delivers the type it can- 100

not follow the type beyond a prescribed point. In other words, much damage and delay have heretofore been caused in the practical use and operation of the machine by reason of 5 the looseness and play of the pusher P, and this I obviate by means of a stop s, so situated on the rigid jaw C' with relation to either the lever p' or to the pusher itself that the downward thrust of the latter is limited and 10 the looseness or play of the cam-roller is taken up or counteracted. As shown in the drawings, the stop s is placed upon the jaw C' in such position that it limits the downward movement of the inner arm of the lever p'; 15 but it is obvious that it might be otherwise arranged with a like result.

What I claim as my invention, and desire to secure by Letters Patent, is—

The combination with the nippers B, for transferring the types to the conveyer and 20 with the distributing mechanism below for receiving the types from the conveyer, of said conveyer C, provided with the type-pusher P, and actuating mechanism, and with the stop s, for limiting the downward thrust of 25 said pusher, substantially in the manner and for the purpose described.

ABBOT AUGUSTUS LOW.
